UNITED STATES PATENT OFFICE

HAROLD WILLIAM SANDERSON, OF COLLESLS, DENHAM, ENGLAND, ASSIGNOR OF ONE-HALF TO THE WALL PAPER MANUFACTURERS LIMITED, OF LONDON, ENGLAND

ROTARY PRINTING MACHINE

Application filed August 24, 1931, Serial No. 559,070, and in Great Britain October 22, 1930.

This invention relates to multi-colour rotary printing machines of the kind having a pressure cylinder; two or more printing rollers; impression rollers intermediate the printing rollers and the pressure cylinder and in frictional engagement with and rotating at the same peripheral speed as the said pressure cylinder, and toothed wheels and pinions for driving the pressure cylinder and the printing rollers, the gear ratio being such that the said toothed wheels and pinions and the said pressure cylinder rotate at the same peripheral speed, and this invention has for its object to provide an improved multi-colour rotary printing machine of the aforesaid kind whereby new printing effects are produced and which is eminently suitable for printing, from surface printing rollers, wallpapers, calicoes and the like.

According to this invention the machine is provided with a printing roller, or printing rollers, having a diameter different from the diameter of the pitch circle of the driving pinion, or pinions, thereof so that the peripheral speed of the said printing roller, or printing rollers, is greater or less than the speed of travel of the web of paper, or other material (hereinafter referred to as a web of paper) passing between this roller, or these rollers, and a yieldable co-acting impression roller, or rollers, whereby the design printed on the said web of paper is either shorter or longer than that on the said printing roller, or rollers, and consequently new printing effects are produced.

I will more particularly describe this invention with reference to the accompanying drawings in which Figures 1 and 2 illustrate, in elevations at right angles to each other, so much of a multi-colour rotary printing machine as is necessary to show the application of this invention thereto.

In the example of machine illustrated 1 indicates a pressure cylinder having a non-

yieldable circumferential surface and rotated at a predetermined speed by means of a toothed wheel 2 to which rotary motion is transmitted from a driving shaft 3 through a toothed wheel 4, secured thereto, and a pinion 5 on a stud secured to the frame A of the machine, which frame is presumed to be removed in Figure 1 in order to show clearly parts that would be obscured by the said frame.

Concentric with the toothed wheel 2 is a toothed wheel 6 to which rotary motion is transmitted from the driving shaft 3 by a toothed wheel 4a. Spaced around the toothed wheel 6 and in engagement therewith are toothed pinions 7 secured to the shafts of surface printing rollers 8 (hereinafter referred to as the printing rollers) for driving the said printing rollers directly. The gear ratio of the aforesaid train of toothed wheels and pinions is such that the peripheral speed of the pressure cylinder 1, the toothed wheel 6 and the toothed pinions 7 in engagement therewith is the same. Situated between the ends of the pressure cylinder 1 and the main frames A are auxiliary frames A' carrying adjustable intermediary rollers 9 (hereinafter referred to as the yieldable impression rollers) covered with any suitable yieldable material. These yieldable impression rollers are situated between the printing rollers 8 and the pressure cylinder 1 and are rotated by their frictional engagement with the said pressure cylinder. The direction of rotation of the yieldable impression rollers 9 is opposite to that of the pressure cylinder 1 and the printing rollers 8. The web of paper 10 passes, as hitherto, between the printing rollers 8 and the yieldable impression rollers 9 and bears with sufficient pressure on the latter rollers as to travel through the machine at a speed equal to the peripheral speed of the pressure cylinder 1, and the said printing rollers only bear on the said

90

web of paper with sufficient pressure as to apply colour thereto, without retarding or accelerating the speed of travel of the said web. The printing rollers 8 are secured to 5 their respective pinions 7 in such manner that the said rollers can be easily removed and replaced by others when desired, and the yieldable impression rollers 9 are rotatably mounted in such manner that they likewise can be removed and replaced by others 10 when desired. By this means any desired pair of co-acting printing and impression rollers can be removed and replaced by another pair having diameters different from 15 the diameters of the pair removed and this can be effected without changing the driving pinions 7 or their position relatively to the toothed wheel 6 with which they engage so that the gear ratio remains unaltered. 20 As the distance between the axes of the driving pinions 7 and the periphery of the pressure cylinder 1 is constant it is preferred when changing a pair of co-acting printing and yieldable impression rollers 25 for another pair of different diameters, as aforesaid, that the sum of the radius of the printing roller and the diameter of the yieldable impression roller of the pair of rollers substituted be equal to the sum of the 30 radius of the printing roller and the diameter of the yieldable impression roller of the pair of rollers removed, so that the slight pressure of the printing rollers is transmitted, through the said yieldable impression rollers, to the pressure cylinder 1. If 35 desired, however, any one, or more than one, of the yieldable impression rollers 8 may be out of contact with the pressure cylinder 1.

In multi-colour printing machines in accordance with this invention any pair, or 40 any desired number of pairs, of co-acting printing and yieldable impression rollers in which the diameter of the printing roller is different from the diameter of the pitch 45 circle of the driving pinion of the said printing roller may be employed and as the web of paper travels through the machine at a constant speed, the designs printed thereon by each of the said printing rollers 50 will be either shorter or longer, according to the relative diameters of the printing roller and the pitch circle of its driving pinion, than that on the said printing roller, thereby producing new printing effects. 55 In multi-colour printing machines of the kind to which this invention relates, it has hitherto been the practice to employ a pressure cylinder of large diameter relatively to that of the printing rollers and to cover the 60 circumference of the said cylinder with rounds of lapping of calico, flannelette, or the like. With this type of pressure cylinder the printing rollers have to bear with greater pressure on the web of paper passing over the said printing rollers than is

necessary for printing in order that the overlap of the blanket at its joint shall be compressed to conform with the diameter of the main portion. Further, owing to the blanket getting dirty or to its constant changing of diameter due to the tightening of the lapping, it is necessary to replace periodically the blanket by another, which necessitates dismantling the machine and in consequence it is out of use for a considerable time. By providing a pressure cylinder 1 having a non-yieldable surface, as aforesaid, that is, by dispensing with the blanket, or other yieldable material on the said pressure cylinder, and interposing between the metallic surface of the said cylinder and each of the printing rollers 8 an intermediary roller 9 covered with yieldable material, as aforesaid, permits of the pressure to be adjusted as required, and this pressure, owing to the absence of the blanket and its overlapping seam, may be less than hitherto so that wear is reduced and less power is required to drive the machine. 70 75 80 85 90

Any suitable, or known, means may be provided for conveying colour to the surface printing rollers and any suitable means may also be provided for rotating the pressure cylinder and the toothed wheel concentric therewith at the same peripheral speed. 95

What I claim is:—

1. In a rotary printing machine having a pressure cylinder, a plurality of printing rollers, impression rollers intermediate the printing rollers and the pressure cylinder and in frictional engagement with and rotating at the same peripheral speed as the said pressure cylinder, gear mechanism for driving the pressure cylinder and the printing rollers, the gear ratio being such that the gears of said gear mechanism and the said pressure cylinder rotate at the same peripheral speed, at least one of said printing rollers having a diameter different from the diameter of the pitch circle of its driving gear, so that the peripheral speed of the said printing roller is different from the speed of travel of a web passing between said roller and its co-acting impression roller whereby the design printed on the said web is caused to differ in length from that on the printing roller. 100 105 110 115

2. A rotary printing machine in accordance with the preceding claim; wherein the pressure cylinder has a non-yieldable surface and the impression rollers intermediate the said pressure cylinder and the printing roller have yieldable surfaces. 120

3. In a rotary printing machine having a pressure cylinder, a plurality of printing rollers, impression rollers intermediate the printing rollers and the pressure cylinder, means for rotating said pressure cylinder and said impression rollers at the same peripheral speed, means for driving some of 125 130 135

said printing rollers at a different peripheral speed than said pressure cylinder and impression rollers.

4. In a rotary printing machine having
5 printing rollers, a pressure cylinder and im-
pression rollers for driving and printing
upon a web, means for driving said pressure
cylinder, impression rollers and web at the
same peripheral speed, means for driving
10 some of said printing rollers at a different
peripheral speed than said web.

In testimony whereof I have signed my
name to this specification, at London, Eng-
land this thirtieth day of July 1931.
